(57) **CLAIM**

We claim an ornamental design for a vehicle serving tray, as shown and described.

DESCRIPTION

FIG. 1 is a front perspective view of a vehicle serving tray showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is an elevational view of one side thereof; and,

FIG. 7 is an elevational view of the other side thereof.
